UNITED STATES PATENT OFFICE.

ALFRED A. ZIEGLER, OF BOSTON, MASSACHUSETTS.

CIRCUIT-WIRE TERMINAL.

1,112,047.

Specification of Letters Patent. Patented Sept. 29, 1914.

Application filed August 11, 1913. Serial No. 784,068.

To all whom it may concern:

Be it known that I, ALFRED A. ZIEGLER, a citizen of the United States, residing at Boston, in the county of Suffolk and State 5 of Massachusetts, have invented an Improvement in Circuit-Wire Terminals, of which the following is a specification.

Certain forms of circuit-wire terminals heretofore made consists of plates having 10 means at one or both ends for connection therewith of one or more circuit-wires, and having provision for a single attaching-screw. The means at one end of the terminal for connection therewith of a circuit-wire 15 consists of a binding-screw which extends through a screw-threaded hole in the end-portion of the plate, and as the plate is quite thin said screw has but a short bearing and easily becomes loosened. Furthermore, such a terminal is liable to turn on 20 its attaching-screw and thereby engage adjacent terminals or objects, causing electrical troubles, and such turning movement also produces a strain on the circuit-wires 25 and their connections with the terminal.

This invention relates to improvements in circuit-wire terminals of this type, and consists in providing one end-portion of the attaching-portion of the plate with an overturned portion, and forming screw-threaded holes respectively in said overturned portion and the attaching-portion, which are arranged in alinement, and employing a binding-screw, made long enough to extend 30 through both holes and to engage the threaded walls thereof; and preferably long enough to project a short distance below the bottom of the attaching-portion of the plate to enter a hole in the support to 35 which the terminal is attached, thereby insuring a long bearing for the binding-screw to prevent it from becoming easily loosened, and also to prevent the terminal from turning on the attaching-screw. As the invention involves essentially one end of the plate only the other end thereof may be provided with any form of circuit-wire connection or may be devoid of a circuit-wire connection.

Figure 1, is a side elevation of a circuit-wire terminal illustrating one embodiment of my invention. Fig. 2, is a plan view of the same. Fig. 3, is an enlarged sectional detail of one end-portion of the terminal.

The terminal consists of an elongated 55 plate of any suitable length and width, but usually made of sheet metal. It has a sub-

stantially flat portion 10 for engagement with its support, which is here shown as arranged intermediate its length, and which forms the attaching-portion, and has a hole 12 through its attaching-portion for attaching-screw 13 by which it is attached to a back-board or other form of support. The end-portion 15 of the plate is here shown as bent upward and formed with a notch 16 for the connection therewith of a circuit-wire, but, so far as my invention is concerned this end-portion of the plate may be provided with any other usual or suitable form of circuit-wire connection, or may be devoid of means for connecting a circuit-wire therewith. The other end-portion of the plate is bent upward and inward as at 20, 21, so that an overturned portion 21 is provided, which is arranged in parallel relation with the flat attaching portion. Screw-threaded holes 22, 23, are extended, respectively, through the overturned portion 21, and the flat attaching-portions which holes are arranged in alinement, to receive a binding-screw 25, the threaded shank of which is made long enough to extend through both threaded holes 22 and 23, and also to project below the flat attaching-portion for a short distance. Said end-portion of the plate may be made slightly flexible or resilient, at least enough so to enable it to be bent slightly in order that the binding-screw, while turning in the hole 22 may be caused to enter the hole 23, in case the parallel arranged portions should not be correctly disposed to enable this result to be otherwise accomplished, and such resiliency is of advantage in preventing the binding-screw from becoming loosened.

The projecting end-portion of the shank of the binding-screw is adapted to enter a hole in the back-board or support to which the terminal is attached, thus to hold the terminal from turning in case its attaching screw is insufficient.

I claim:

1. The circuit-wire terminal herein described consisting of an elongated plate, one end-portion of which is bent upward and inward to form a flat attaching-portion and an overturned-portion, arranged in parallel relation, both said overturned-portion and attaching-portion having screw-threaded holes through them, arranged in alinement, and a binding-screw for a circuit-wire extended through and engaging said thread-

ed holes, the attaching-portion also having a hole through it for an attaching-screw.

2. The circuit-wire terminal herein described consisting of an elongated plate of sheet metal, one end-portion of which is bent upward and inward to form a flat attaching-portion and an overturned-portion, arranged in parallel relation, the latter being made slightly resilient, and both having screw-threaded holes through them arranged in alinement, and a binding-screw

for a circuit-wire extended through and engaging said threaded holes, the attaching-portion also having a hole through it for an attaching-screw.

15

In testimony whereof, I have signed my name to this specification, in the presence of two subscribing witnesses.

ALFRED A. ZIEGLER.
